UNITED STATES PATENT OFFICE.

GEBHARD JAEGER, OF COLUMBUS, OHIO.

CONCRETE-MIXING MACHINE.

Application filed April 27, 1923. Serial No. 634,996.

To all whom it may concern:

Be it known that I, GEBHARD JAEGER, a citizen of the United States, residing at Columbus, in the county of Franklin and State of Ohio, have invented a certain new and useful Improvement in Concrete-Mixing Machines, of which the following is a specification.

This invention relates more particularly to the type of concrete mixer that has an axially rotated mixing drum having a single opening for charging and discharging the drum and means for oscillating the drum from charging to discharging position, and the invention has for its object to provide an improved construction of hand-operated means whereby the oscillation of the drum may be conveniently accomplished.

The invention is embodied in the example herein shown and described, the features of novelty being finally claimed.

In the accompanying drawing—

Figure 1 is a side view showing a mixer equipped with the invention.

Fig. 2 is a top plan view showing as far as may be in such a view the details of the invention.

In the views 5 designates the mixing drum which is of a usual type and having a single charging and discharging opening at 5^a. The mixing drum is mounted centrally at its bottom to turn axially on a swinging yoke 6 supported in bearings on a suitable frame 4; and said drum has a circumferential rack 30 to be engaged by a suitable pinion (not shown) for turning it, it not being necessary to show the details of that because not a part of the present invention. One of the trunnions of the swinging yoke 6 has fixedly connected to it a tubular member 7 the opening of which stands at right angles to the axis of the trunnion, and through this opening is extended one arm 8 of a bent rod. This arm 8 of the bent rod is secured to the tubular member by means of a collar 15

fixed with a set screw 15^a to the rod so that the arm 8 is capable of rocking on its axis in the tubular member. The other arm 8^a of the bent rod can therefore oscillate or swing back and forth in a plane at an angle to the axis of the arm 8. The tubular member 7 has a projecting stop 7^a cast with it to limit the oscillation of the arm 8^a outward from the drum.

Mounted on the top of the trunnion-bearing 3 is a casting or member 9 the base of

which is provided with slots 10 through which bolts 11 are passed to secure the casting to the trunnion bearing. By this means the member 9 is rendered adjustable so that the mixing position of the drum can be changed. The member 9 has two lugs 12 and 13 the latter being the longer, said lugs forming a bifurcate stop, the lugs being spaced sufficiently to allow the arm 8^a to stand between them.

The member 9 has a stop 14 against which the yoke strikes to limit the extreme movement of the yoke and drum in either direction.

When the arm 8^a is placed between the lugs 12 and 13, as shown in full lines in both the views, the mixing drum is held in charging and mixing position, and the workman can so leave it to charge the drum and to turn the drum to mix the charge. After drawing the arm 8^a out from between the lugs 12 and 13 the drum can be swung over to the left to discharging position indicated by broken lines Fig. 1. In thus swinging the drum over to discharging position the workman uses arm 8^a and 8 in succession in the order stated and in bringing the drum back to charging and mixing position he uses them in succession in reverse order. The lug 13 also serves to arrest the drum when swung to mixing position.

The forms of the parts can be changed without departing from the gist of the invention as claimed.

What I claim is:

1. In a mixing machine, the combination of a supporting frame, a mixing drum, a supporting yoke for the drum having a trunnion turning in said frame, a pair of arms connected with the trunnion for swinging the drum, one of said arms mounted to swing toward and from the frame, and a stop with which said arm may be engaged to arrest the same.

2. In a mixing machine, the combination of a supporting frame, a mixing drum, a supporting yoke for the drum having a trunnion turning in said frame, a tubular member secured to said trunnion and a bent bar forming two arms for swinging the trunnion and drum, said bar secured by one of its arms to rock on its axis in said tubular member while the other swings toward and from the drum.

3. In a mixing machine, the combination

of a supporting frame, a mixing drum, a supporting yoke for the drum having a trunnion turning in said frame, a tubular member secured to said trunnion, a bent bar 5 forming two arms for swinging the trunnion and drum, said bar secured by one of its arms in said tubular member to turn on its axis in said tubular member while the other swings toward and from the drum and a 10 bifurcate stop into which said other arm can swing.

4. In a mixing machine, the combination 15 of a supporting frame, a mixing drum, a supporting yoke for the drum having a trunnion turning in said frame, a tubular member secured to said trunnion, a bent bar forming two arms for swinging the trunnion and drum, said bar secured by one of its arms in said tubular member to turn on its axis 20 in said tubular member while the other

swings toward and from the drum and an adjustable stop into which said other arm can swing.

5. In a mixing machine, the combination 25 of a supporting frame, a mixing drum, a supporting yoke for the drum having a trunnion turning in said frame, a tubular member secured to said trunnion, a bent bar forming two arms for swinging the trunnion and drum, said bar secured by one of its 30 arms in said tubular member to turn on its axis in said tubular member while the other swings toward and from the drum, a bifurcate stop into which said other arm can swing inwardly toward the mixing drum 35 and means on the tubular member for limiting the outward swing of said arm from the mixing drum.

GEBHARD JAEGER.
